UNITED STATES PATENT OFFICE.

GUSTAF BIRGER BIRCH, OF BROOKLYN, NEW YORK, ASSIGNOR TO CAMERON MACHINE COMPANY, OF BROOKLYN, NEW YORK, A CORPORATION OF NEW YORK.

COLLAPSIBLE MANDREL.

1,315,177.

Specification of Letters Patent. Patented Sept. 2, 1919.

Application filed October 20, 1917. Serial No. 197,591.

To all whom it may concern:

Be it known that I, GUSTAF B. BIRCH, a citizen of the United States, and a resident of the borough of Brooklyn, in the city of

5 New York, county of Kings, and State of New York, have invented certain new and useful Improvements in Collapsible Mandrels, of which the following is a specification.

10 The present invention relates generally to collapsible mandrels such as are utilized, for instance, in rewinding machines for rewinding coils of material on the same when in its expanded position, the mandrel being 15 subsequently collapsed for the purpose of permitting removal of the coils therefrom.

The main object of this invention is to produce a collapsible mandrel of very simple construction which will at the same time be reliable and effective in operation. In 20 the art of collapsible mandrels, it is a general custom to effect the expansion and collapsing of the mandrel by means of lengthwise displacement of the outer and inner 25 members constituting it; and this is most usually effected by means of cam surfaces of somewhat complicated character. The result of such construction is that it is difficult to produce collapsible mandrels of small 30 diameter because of the amount of space required by the expanding and collapsing elements; and also in making mandrels of large diameter, difficulty is encountered because of the necessity of making the core 35 disproportionate in size to the size of the mandrel as a whole in order to afford space within a given diameter for the collapsing and expanding elements.

The main feature of the invention resides 40 in a collapsible mandrel comprising a core and a shell of resilient sheet material slitted longitudinally into segments that collapse and expand uniformly at opposite ends of the mandrel.

45 Specifically, the shell of sheet material that surrounds the core is composed of integral segments partially separated by longitudinal slits, each slit running clear from one end of the shell and terminating short 50 of the other end, the adjacent slits extending from opposite ends of the shell. The result is a shell of sheet material that is divided into circumferential adjacent segments by means of longitudinal slits, each segment being connected at opposite ends to the next

adjacent segment by an integral portion. The integral portions of each section extend in opposite directions circumferentially at opposite ends.

Other features of construction will appear 60 as the specification proceeds.

In the accompanying drawings:

Figure 1 is what may be called a top plan view, partly broken away, in section of a collapsible mandrel embodying the invention. 65

Fig. 2 is a vertical sectional view on the line 2—2 of Fig. 5.

Fig. 3 is a vertical sectional view on the line 3—3 of Fig. 5. 70

Fig. 4 is a vertical sectional view on the line 4—4 of Fig. 5.

Fig. 5 is what may be called a side elevation of the mandrel partly in section and broken away, showing the shell in its expanded position. 75

Fig. 6 is a view similar to Fig. 5 showing the mandrel collapsed.

Fig. 7 is a view, partly in elevation and partly in section, of a modified form of the invention. 80

Fig. 8 is a vertical sectional view on the line 8—8 of Fig. 7.

Fig. 9 is a diagrammatic view showing a shell that has been cut and laid out as a flat blank. 85

1 indicates a core of any suitable construction and is here shown as a simple bar or shaft. 2 is the outer shell composed of a plurality of segments that are formed by means of longitudinal slits 3, each slit running clear from one end of the shell and terminating short of the other end, the adjacent slits extending from opposite ends of the shell. This will be apparent from the diagram of Fig. 9 in which the oppositely disposed slits are clearly shown. The result is that the segment 4 is connected at its opposite ends to the next adjacent segment by an integral portion 5, said integral portion extending in opposite directions circumferentially at opposite ends as shown. 90

In Figs. 1 to 6 inclusive there are but two segments while in Figs. 7 and 8 there are four segments. 100

Suitable means for expanding and collapsing the mandrel are provided, in the present instance taking the form of projections 6 preferably having cam surfaces 7 carried by the core, there being, prefer- 110

ably, a plurality of such members in alignment with each other as shown more particularly in Fig. 1. In line with these projections are perforations or openings 8 in 5 the shell. 9 indicates a member on the core that extends into the closed slot 10 of the shell to preserve the members 6 in alignment with openings 8. It will be apparent that, if the core and shell are displaced 10 longitudinally with respect to each other, and sufficiently to bring the projection 6 into the plane of the openings 8, the resiliency of the material of the shell will cause said shell to collapse in the manner indicated 15 in Fig. 6; and that the collapsing action of the shell will be substantially uniform at opposite ends thereof because of the oppositely disposed slits. Also, when the core and shell are displaced longitudinally 20 with respect to each other in the opposite direction, the cam surfaces 7 of the member 6 will cause the shell to expand as these surfaces bear against the inside of the shell in the manner indicated in Fig. 5. The amplitude 25 of slot 10 is such that the member 9 will remain in the plane thereof whether or not the mandrel is in its expanded or collapsed position so that the parts 6 and 8 will be maintained in alignment 30 with each other. It will be understood that the extent of the projection of the member 6 outside the core 1 should preferably not be greater than the thickness of the shell so that when the parts are in their 35 collapsed positions, as in Fig. 6, said member 6 will not project beyond the uniform circumference afforded by the shell. The pin 9 is located outside of that part of the mandrel on which the rewound coils are 40 placed and may project somewhat beyond the outer circumference of the shell when in its collapsed position.

In Figs. 7 and 8 there is shown a modification in which four segments are provided in the same manner as previously described for two segments.

In order to prevent torsional twisting of

the segments when rewinding material on the mandrel, suitable means are employed that, in this instance, take the form of projections 11 carried by the shell and sliding in engagement with grooves 12 of the core. It will be understood that this construction may be applied either to the form shown in Fig. 1 or to the form shown in Fig. 7. It will also be understood that when these means are employed, the members such as 9 and 10 may be omitted, if desired, since members 11 and 12 will maintain proper alignment of the parts. 60

I claim:

1. A collapsible mandrel comprising: a core, a shell of sheet material surrounding the core composed of integral segments partially separated by longitudinal slits, each slit running clear from one end of the shell and terminating short of the other end and adjacent slits extending from opposite ends of the shell, means for expanding and collapsing the shell by a relative lengthwise movement of the core and shell including projections on the core and openings in the shell, and means for maintaining the co-operating expanding means in alignment with each other. 70

2. A collapsible mandrel comprising: a core, a shell of sheet metal surrounding the core composed of integral segments partially separated by longitudinal slits, each slit running clear from one end of the shell and terminating short of the other end and adjacent slits extending from opposite ends of the shell, means for expanding and collapsing the shell by a relative lengthwise movement of the core and shell including projections on the core of a height substantially equal to the thickness of the shell and openings in the shell, and means for maintaining the co-operating expanding means in alignment with each other. 80

Signed at Brooklyn, in the county of Kings and State of New York, this 11 day of October, 1917.

GUSTAF BIRGER BIRCH.
